UNITED STATES PATENT OFFICE.

GEORGE W. MILLER, OF ROCHESTER, NEW YORK.

HINGED LAST.

1,094,673.

Specification of Letters Patent. Patented Apr. 28, 1914.

Application filed April 26, 1913. Serial No 763,896.

To all whom it may concern:

Be it known that I, GEORGE W. MILLER, a citizen of the United States, residing at Rochester, in the county of Monroe and State of New York, have invented certain new and useful Improvements in Hinged Lasts, of which the following is a specification.

This invention relates to lasts of the type having hinged toe and heel parts, and has for its object to provide a last with an improved hinge structure and arrangement whereby its strength will be increased to an extent sufficient to stand the wear and strain incident to the use of the last.

A further object of the invention is to provide an improved locking device for holding the last parts in straight or rigid position.

20 The invention also comprises an improved form of knuckle joint with a hinge connection of great strength, without requiring the wood to be cut away to such an extent as to interfere with the strength of the last.

25 Further objects and advantages will appear from the following description and the accompanying drawings.

In the drawings—Figure 1 is a side elevation, partly in longitudinal section, of the last. Fig. 2 is a detail of the locking device. Fig. 3 is a top plan view of the heel part. Figs. 4 and 5 are side and end views of the same. Figs. 6 and 7 are end and side views of the toe part of the last. Fig. 8 is a 30 perspective view of a hinge member. Fig. 9 is a side elevation of a modification.

Referring specifically to the drawings, 1 indicates the toe part of the last and 2 the heel part.

40 3 is the hinge member, comprising a cylindrical tubular body having ears 19 projecting at one end thereof, these ears being flattened and lying in parallel vertical planes, with pintle holes 20 through the same, and a hole 23 through the front end to receive a pin 4, inserted through a bore 12 to hold the hinge member in the bored socket 14 made to receive it in the toe part of the last. The hinge member is conveniently 45 stamped in a blank from sheet metal and then bent to circular form, bringing the edges 21 together as shown in Fig. 8.

50 The knuckle joint between the sections is formed by sawing the heel part with a transverse knuckle 20 extending across the meeting face, which fits in a sawed socket 31 in

the toe part. The knuckle 30 has vertical kerfs 13 to receive the ears 19 of the hinge member, and has a cross bore 11 to receive the pintle 5 which extends through the same and also through the holes 20 in the ears 19. The curved surfaces of the knuckle 30 and socket 31 are concentric with the axis of the pintle 5. Below the joint the toe part is sawed to produce a transverse rearwardly extending projection 15 which stops against the complementary shoulder 16 of the heel part when the last is straightened. The surfaces of the knuckle 30 and socket 31 are in close contact in all positions of the last parts, 70 and the relatively narrow kerfs 13 are the only parts of the wood which are cut away across the knuckle, which is where the principal strain comes, so the remaining wood provides a strong and rigid joint, in connection with the hinge member 3 fitting closely 75 in the socket 14 in the toe part.

70 The locking device consists of a sleeve 7, which is inserted in a bore 10 extending vertically downward from a shoulder on the front end of the heel part, and this sleeve houses a bent catch 6 which is capable of being turned therein and which extends below the lower end of the sleeve where it is provided with a head 9 and a spring 8 coiled 80 between said head and the sleeve 7, said spring tending to pull the catch 6 down so as to hold its free end in close engagement with the rear end of the toe part of the last when said last is straightened. An extension 22 on the sleeve forms a stop for the catch when it is turned crosswise preparatory to flexing the last on the hinge. A wear plate 85 may be set in the toe part of the last where the catch 6 presses against it, and this catch 90 is of such length that it will span the space between the toe and heel parts and prevent flexing of the last when not desired. To release the catch, it is pulled up slightly, against the tension of the spring 8, and 100 turned to inoperative position, and in order to permit this to be done without the end of the catch projecting beyond the surface of the side of the last, the bore 10 is offset to one side of the middle line, so as to give space 105 for the catch to swing around on the other side within the plane of the side of the last.

110 In the modified form shown in Fig. 9 the cut of the knuckle is changed to provide a shoulder 18 which when the last is straightened stops against a complementary shoulder formed on the toe part of the last. This

increases somewhat the rigidity of the structure.

Having described my invention, what I claim as new is:—

- 5 A hinged last comprising heel and toe parts, one of said parts having a transverse knuckle with two spaced vertical kerfs therein, and the other part fitting against said knuckle and having a longitudinal socket, a
- 10 cylindrical hinge member fastened in said socket and having two vertical ears project-

ing at opposite sides of one end thereof and fitting in the kerfs, and a hinge pin extending through the ears and through the parts of the knuckle between and on the outer 15 sides of the kerfs.

In testimony whereof, I affix my signature in presence of two witnesses.

GEO. W. MILLER.

Witnesses:

ALFRED T. WANGMAN,
ALFRED J. MCGUIRE.
